UNITED STATES PATENT OFFICE.

OTTO GEISLER, OF CHICAGO, ILLINOIS, ASSIGNOR OF ONE-THIRD TO GEORGE SETH, OF CHICAGO, ILLINOIS.

COLLAPSIBLE GAS CONTAINER WITH INTERNAL BRACING.

Application filed February 17, 1928. Serial No. 255,009.

My invention relates to improvements in collapsible gas containers with internal bracings for airships of the lighter than air type, and it consists in the combinations, constructions, and arrangements herein described and claimed.

An object of my invention is to provide a collapsible gas container for airships in which a major portion of the internal bracing for the airship is contained within the collapsible gas container and the bracing being arranged to collapse so as to permit the gas containers to be entirely collapsed as when emptying gas therefrom.

15 A further object is to provide a gas container for an airship of such a type that the containers may be quickly and easily deflated, and entirely excluding all air from the container so that the latter may be inflated with 20 a gas free from air.

A further object is to provide a gas container for airships in which the internal bracing for supporting the airship may be easily and quickly collapsed for permitting 25 a free movement of the container.

A further object is to provide a gas container for an airship of such a type that a puncture through the body of the airship in any given place will not necessarily force 30 the ship to descend.

A further object is to provide a gas container in which automatic means is provided for receiving gas which otherwise would be caused to pass into the atmosphere and thus 35 wasted as when the ship passes into a higher altitude.

Other objects and advantages will appear 40 in the following specification, and the novel features of the invention will be particularly pointed out in the appended claims.

My invention is illustrated in the accompanying drawings, forming part of this application, in which

Figure 1 is a side elevation of an airship 45 embodying my invention,

Figure 2 is a transverse sectional view through the ship,

Figure 3 is a sectional view taken substantially along the line 3—3 of Figure 2,

50 Figure 4 is an enlarged detail view of a portion of the device shown in Figure 3,

Figure 5 is an enlarged diagrammatic showing of a part of the internal bracing,

55 Figure 6 is a detail view of a portion of my device,

Figure 7 is an end view of the device shown in Figure 6,

Figure 8 is an enlarged detail view of a portion of my device,

Figure 9 is an enlarged detail view of a 60 portion of the bracing,

Figure 10 is a detail view showing a portion of one of the gas containers,

Figure 11 is a top plan view of the device shown in Figure 10, and

Figure 12 is a detail of an automatic valve.

In carrying out my invention, I make use of an airship 1 substantially as shown in Figure 1. The airship, as will be seen from Figure 2, is provided with an outer casing 2.

This casing is preferably made from aluminum sheeting and is substantially cylindrical in cross section. The casing 2 is gas-proof. The casing is secured and supported by means of a series of supporting rings 3, see Figure 75

1. The rings 3, as will be seen from Figure 6, are constructed from any suitable material, such as aluminum angles 4 supported by means of bracing 5. The rings 3, which may be termed the outer rings, are held in spaced

80

relation with respect to inner rings 6, see Figure 2. Suitable supporting members 7, preferably of tubular construction such as is shown in Figure 6, rigidly secure the outer rings 3 and the inner rings 6 as shown in 85

Figure 2. Suitable bracing members 8 further support the outer and inner rings in their respective positions.

The airship 1 is provided with a central 90 longitudinally disposed bracing member 9, see Figure 3. The member 9 is preferably a

relatively large pipe. Bracing rods 10 are disposed radially with respect to the supporting member 9 and are secured to the inner rings 6 as shown in Figure 8. It will thus

95 be seen that the shaft or pipe 9 is supported centrally with respect to the rings 3 and 6 and also that the shaft serves as a supporting member for the rings.

Referring now to Figure 3, I have shown 100 a plurality of bracing diagonals 11 which are hingedly secured at 12 to the alternate rings

3. The diagonals 11 are hinged substantially at a mid point 13 and have their inner ends

105 secured to the shaft 9 by means of a compressed air actuated device 14 such as that shown in Figure 4.

The inner ends of the diagonals 11 are provided with connecting members 15 which may be moved into locked engagement with a cup-

110

shaped device 16 carried by the outer end of pistons 17 as shown in Figure 4. The pistons may be reciprocated within housings 18 by means of compressed air or any suitable fluid medium through pipes 19. The housings 18 are mounted upon the shaft 9 as shown in Figure 3.

The alternate rings 3 to which the diagonals 11 are secured are substantially the same in construction as the alternate rings shown in Figure 3, the difference in the rings being that the rings to which the diagonals 11 are secured are provided with suitable bracing members 20, such as that shown diagrammatically in Figure 5. These bracing members may be of any suitable material, preferably of flat metal construction, and serve a twofold purpose—that additional bracing is provided for the ship, and also a backing or supporting means for the collapsible gas containers, as will be explained hereinafter. Referring now to Figure 3, it will be noted that the diagonals 11 are encased within suitable gas containers 21. The containers 21 are preferably secured to the rings R and, when inflated, move longitudinally with respect to the ship and away from the rings to which they are secured.

The rings 3 are held in spaced relation by means of longitudinal bracing means 22. As will be seen from Figure 6, the rings 3 are secured to the supporting members 22. The inner rings 6 are also supported against longitudinal movement by means of longitudinal bracing 23. In Figure 8, I have shown the manner in which the radially disposed bracing rods 10 are secured to the longitudinal bracing members 23. The longitudinal bracing members 23 are supported at a mid point between the rings 3 by means of fixed diagonal members 24.

The gas containers 21 are provided with sleeve means 25 which are arranged about the longitudinal bracing 23 as shown in Figure 3. A sleeve 26 is also secured to each of the containers for sealing purposes about the shaft 9. Referring now to Figures 3, 10, and 11, it will be seen that the gas containers 21 are constructed so that during inflation or deflation the containers may move without interference from the diagonal bracings 24. When the containers 21 are inflated as shown in Figure 11, the pocket portions 27 are disposed as shown. It will be seen that I have provided a pocket portion 27 for each of the fixed diagonal members 24 and that the containers 21 may be so collapsed by reason of the pockets 27 that a maximum expulsion of gas from the containers is attained. When the containers 21 are entirely collapsed, as shown in a section of Figure 3, the pocket portions 27 are disposed as at 28. The containers 21 pass underneath folding bars 29 during the process of collapsing.

An auxiliary gas container 30 is provided

within each of the containers 21. The proportion of the containers 30 with respect to the containers 21 is shown in Figure 2. Suitable walls 31 are provided between which the auxiliary gas containers 30 are disposed. A pipe 32 is secured to each of the containers 30 and is provided with an automatic valve 33 which is disposed within the containers 21. A suitable outlet valve 34 is also secured to the auxiliary containers 30. A corridor 35 is situated between the walls 31 as shown in Figure 2.

In Figure 3, I have shown the diagonals 11 disposed in their bracing position and also the position of the diagonals when the gas containers 21 are in their collapsed position. A suitable wire rope or other means 36 is secured to each of the diagonals relatively near the hinge 13 and passes around pulley means 37. A similar rope or wire 38 is secured to the connecting members 15, the rope passing through a pulley 39 carried by the cup-shaped devices 16.

The wires 36 and 38 are passed to any suitable location in the ship and may be actuated manually or by any suitable mechanism which forms no part of the present invention.

Means for permitting gas within the containers 21 to pass into the atmosphere consists of a tubular member 40 disposed within each of the containers and passing through the casing 29 at 41. The inner ends of the tubes 40 are provided with suitable automatic valve means for permitting the gas to pass through the tubes. Suitable means 42 is provided for permitting the inlet and outlet of air surrounding the auxiliary containers 30. Any suitable means 43 is provided for permitting gas to be passed into the containers 21.

From the foregoing description of the various parts of the device, the operation thereof may be readily understood. When it is desired to collapse the containers for excluding the gas, the diagonals 11 are moved into the position shown at the right in Figure 3. Movement of the wires 36 permits the diagonals to be so collapsed that the containers 21 will assume the position shown, thereby excluding all of the gas within the container. Before the diagonals 11 can be collapsed, the connecting members 15 must of course be disconnected from the cup-shaped members 16.

Let us assume now that one of the gas containers 21 is entirely collapsed, as shown at the right in Figure 3. The first step of course is to pass suitable gas into the container, whereupon the latter will expand from the ring R and assume the position shown at the left. The wires 38 are then pulled for moving the connecting members 15 into the cup-shaped members 16, thereby operatively connecting the diagonals with the pistons 17. Compressed air may then be passed into the housings 18 for moving the pistons 17 in-

wardly, thereby placing each of the diagonals under proper tension for rigidly bracing the ship. Before the diagonals 11 can be moved into their collapsed position, the pistons 17 must of course be moved back to their full line position shown in Figure 4. When the containers 21 are sufficiently inflated, they of course bear against the alternate rings 3 provided with the additional bracing members 20.

Let us assume that the ship is in the air and that it is necessary to pass the gas from the containers 21 to the auxiliary containers 30. Passage of gas into the auxiliary containers 30 occurs when the ship passes into a higher altitude, at which time the external pressure upon the exterior of the ship is reduced so that it is necessary to reduce the pressure within the ship. This transfer or passage of gas is automatic in that the valve 33 is opened by the pressure of the gas, whereupon the gas may pass into the auxiliary containers 30. The gas within the auxiliary containers 30 may be passed back to the containers 21 through the valves 34. These valves may be operated by any suitable means not shown.

In referring to Figure 3, it will be noted that the sleeve means 25 which are associated with the longitudinal bracing members 23, in addition to performing a sealing function, also coact with the container 21 during the process of expansion so that the possibility of rotation of the container is limited. This is an important feature since it will be observed that the pockets 27 must necessarily move in a substantially predetermined path so that the pockets will enclose the fixed diagonal members 24. Since a sleeve 25 is provided for each of the longitudinal bracing members 23, it will be understood that the containers 21 are accurately guided so that a maximum amount of expansion is attained.

In Figure 2, I have shown bracing means 44 disposed between the walls 31. The brace is encased within a suitable sleeve which is integral with the auxiliary gas container 30. The sleeve of course is a sealing means for preventing the passage of gas from the auxiliary container 30 to the exterior thereof. Sleeve means 45 is disposed about that part of the inner ring 6 which is disposed within the walls 31. The compressed air actuated device 14, as shown in Figure 4, is disposed within the container 21 as shown at the right in Figure 2. It is understood of course that each diagonal 11 is provided with a piston 17. In Figure 3, I have shown only a sufficient number of the compressed air actuated devices to make clear the manner in which these devices are associated with the diagonals. Since the construction and operation of the diagonals are identical, I have shown in Figure 3 only a sufficient number to illustrate the relative position and operation of each of the coacting members.

The corridor 35 may be used for various purposes, such as providing a passageway for the operators of the airship, and also a means for storing various necessities, such as fuel tanks, etc.

Suitable means 46 is provided for each of the pistons 17, as shown in Figure 4. When the pistons are moved inwardly for the purpose of placing the diagonals under proper tension, the means 46 engage the pistons so as to hold the latter, thereby locking the pistons until it is desired to release them. Any suitable means may be provided for actuating the locking means 46 at will.

I have used the term "pockets" to define the construction of the gas containers 21 at those points where the containers pass the fixed diagonal members. The term "pockets" has been used for the want of a better term. It will be noted from my drawings that when the main gas containers 21 are in their collapsed position, certain of the fixed diagonal members are disposed within the pocket portions 27. When the gas containers 21 are expanded, it will be seen that the pocket portions 27 permit the containers to expand to their maximum position and that the pocket portions 27 are moved and fold around another set of the fixed diagonal members. This construction provides a gas container in which displacement due to internal bracings and the like is reduced to a minimum. It will be seen that the construction of the pockets 27 is such that the gas containers may be inflated or deflated with no interference from the internal fixed bracing and that the pockets are of such a type that the weight of the containers is very little affected by the additional cloth in the pockets.

After the containers 21 have been collapsed and the gas has passed therefrom, a vacuum is created within the containers for the purpose of securing one hundred per cent expulsion of air therefrom so that the containers when they are again inflated are filled with one hundred per cent gas. The vacuum may be created by any suitable means not shown.

I claim:

1. The combination of an outer casing for an airship of the lighter than air type, supporting means disposed in spaced relation, collapsible gas-containing means secured to certain of said spaced-apart supporting means and adapted to be inflated and to be supported by the other of said spaced-apart supporting means, and collapsible bracing means secured to certain of said spaced-apart means and disposed within said gas-containing means.

2. The combination of an outer casing for an airship of the lighter than air type, supporting means disposed in spaced relation, collapsible gas-containing means secured to certain of said spaced-apart supporting

- means and adapted to be inflated and to be supported by the other of said spaced-apart supporting means, collapsible bracing means secured to certain of said spaced-apart supporting means and disposed within said gas-containing means, and auxiliary gas-containing means disposed within said collapsible gas-containing means for receiving gas from said collapsible gas-containing means.
- 10 3. The combination of an outer casing for an airship of the lighter than air type, supporting means disposed in spaced relation, collapsible gas-containing means secured to certain of said spaced-apart supporting means and adapted to be inflated and to be supported by the other of said spaced-apart supporting means, collapsible bracing means secured to certain of said spaced-apart supporting means and disposed within said gas-containing means, auxiliary gas-containing means for receiving gas from said collapsible gas-containing means, and automatic means operatively connecting said auxiliary gas-containing means with said collapsible gas-containing means.
- 15 4. The combination of an outer casing for an airship of the lighter than air type, supporting means disposed in spaced relation, collapsible gas-containing means secured to certain of said spaced-apart supporting means and adapted to be inflated and to be supported by the other of said spaced-apart supporting means, collapsible bracing means secured to certain of said spaced-apart supporting means and disposed within said gas-containing means, auxiliary gas-containing means for receiving gas from said collapsible gas-containing means, automatic means operatively connecting said auxiliary gas-containing means with said collapsible gas-containing means, and means operatively connected with said collapsible bracing means for placing said last-named means under bracing tension.
- 20 5. The combination of an outer casing for an airship of the lighter than air type, supporting means disposed in spaced relation, collapsible gas-containing means secured to certain of said spaced-apart supporting means and adapted to be inflated and to be supported by the other of said spaced-apart supporting means, collapsible bracing means secured to certain of said spaced-apart supporting means and disposed within said gas-containing means, auxiliary gas-containing means for receiving gas from said collapsible gas-containing means, automatic means operatively connecting said auxiliary gas-containing means with said collapsible gas-containing means, means operatively connected with said collapsible bracing means for placing said last-named means under bracing tension, and means for supporting the collapsible bracing in its collapsed position.
- 25 6. A collapsible gas container comprising

supporting means, movable supporting members disposed on the opposite sides thereof, and collapsible gas-containing means secured to said supporting means and enclosing said movable supporting members.

7. The combination of an outer casing for an airship of the lighter than air type, spaced-apart supporting members disposed within the casing, a central longitudinally disposed bracing member disposed within the casing, collapsible gas-containing means secured to certain of said spaced-apart supporting members, and sleeve means integral with said gas-containing means and secured to the central longitudinally disposed bracing member.

8. The combination of an outer casing for an airship of the lighter than air type, spaced-apart supporting members disposed within the casing, a central longitudinally disposed bracing member disposed within the casing, collapsible gas-containing means secured to certain of said spaced-apart supporting members, sleeve means integral with said gas-containing means and secured to the central longitudinally disposed bracing member, and a plurality of longitudinally disposed bracing means.

9. The combination of an outer casing for an airship of the lighter than air type, spaced-apart supporting members disposed within the casing, a central longitudinally disposed bracing member disposed within the casing, collapsible gas-containing means secured to certain of said spaced-apart supporting members, sleeve means integral with said gas-containing means and secured to the central longitudinally disposed bracing member, a plurality of longitudinally disposed bracing means, and sleeve means integral with said collapsible gas-containing means and secured to said plurality of longitudinally disposed bracing means.

10. The combination of an outer casing for an airship of the lighter than air type, spaced-apart supporting members disposed within the casing, a central longitudinally disposed bracing member disposed within the casing, collapsible gas-containing means secured to certain of said spaced-apart supporting members, sleeve means integral with said gas-containing means and secured to the central longitudinally disposed bracing member, a plurality of longitudinally disposed bracing means, sleeve means integral with said collapsible gas-containing means and secured to said plurality of longitudinally disposed bracing means, and auxiliary gas-containing means disposed within each of said collapsible gas-containing means.

11. The combination of an outer casing for an airship of the lighter than air type, spaced-apart supporting members disposed within the casing, a central longitudinally disposed bracing member disposed within the casing, collapsible gas-containing means secured to

- certain of said spaced-apart supporting members, sleeve means integral with said gas-containing means and secured to the central longitudinally disposed bracing member, a plurality of longitudinally disposed bracing means, sleeve means integral with said collapsible gas-containing means and secured to said plurality of longitudinally disposed bracing means, auxiliary gas-containing means disposed within each of said collapsible gas-containing means, and means actuated by the pressure of gas within said gas-containing means for operatively connecting the latter with said auxiliary gas-containing means.
12. The combination of an outer casing for an airship of the lighter than air type, spaced-apart supporting members disposed within the casing, a central longitudinally disposed bracing member disposed within the casing, collapsible gas-containing means secured to certain of said spaced-apart supporting members, sleeve means integral with said gas-containing means and secured to the central longitudinally disposed bracing member, a plurality of longitudinally disposed bracing means, sleeve means integral with said collapsible gas-containing means and secured to said plurality of longitudinally disposed bracing means, auxiliary gas-containing means disposed within each of said collapsible gas-containing means, means actuated by the pressure of gas within said gas-containing means for operatively connecting the latter with said auxiliary gas-containing means, and means actuated by the pressure of gas within the collapsible gas-containing means for conveying gas to the exterior of said airship.
13. The combination of an outer casing for an airship of the lighter than air type, a plurality of spaced-apart supporting members disposed within the casing, collapsible gas containing means alternately secured to certain of said spaced-apart supporting members, a plurality of longitudinally disposed bracing members concentrically spaced away from said casing, and diagonal bracing members associated with said longitudinally disposed bracing members for rigidly supporting the latter and said spaced-apart members, said collapsible gas containing means being provided with pockets arranged to receive certain of said diagonal bracing members when said collapsible gas containing means is in an inflated or a deflated condition.
14. The combination of an outer casing of an airship of the lighter than air type, a plurality of spaced-apart supporting members disposed within the casing, collapsible gas containing means alternately secured to certain of said spaced-apart supporting members, a plurality of longitudinally disposed bracing members spaced away from said casing, rigid diagonal bracing members associated with said longitudinally disposed bracing members for supporting the latter and said spaced-apart members, said collapsible gas containing means being provided with pockets arranged to receive certain of said diagonal bracing members when said collapsible gas containing means is in an inflated or a deflated condition, and collapsible bracing disposed within said collapsible gas containing means for bracing said airship.
15. The combination of an outer casing of an airship of the lighter than air type, a plurality of spaced-apart supporting members disposed within the casing, collapsible gas containing means alternately secured to certain of said spaced-apart supporting members, a plurality of longitudinally disposed bracing members spaced away from said casing, rigid diagonal bracing members associated with said longitudinally disposed bracing members for supporting the latter and said spaced-apart members, said collapsible gas containing means being provided with pockets arranged to receive certain of said diagonal bracing members when said collapsible gas containing means is in an inflated or a deflated condition, collapsible bracing disposed within said collapsible gas containing means for bracing said airship.
16. A collapsible gas container comprising supporting means, movable supporting members disposed on the opposite sides thereof, collapsible gas containing means secured to said supporting means and enclosing said movable supporting members, and means for placing said movable supporting members under bracing tension.
17. The combination of an outer casing for an airship of the lighter than air type, a plurality of spaced-apart supporting members disposed within the casing, a plurality of longitudinally disposed bracing members disposed within the casing, and inflatable gas containing means secured to certain of said spaced-apart supporting members, said inflatable gas containing means being provided with a plurality of sleeves disposed upon said longitudinally disposed bracing members.
18. The combination of an outer casing for an airship of the lighter than air type, a plurality of spaced-apart supporting members disposed within the casing, a plurality of longitudinally disposed bracing members disposed within the casing, inflatable gas containing means secured to certain of said spaced-apart supporting members, said inflatable gas containing means being provided with a plurality of sleeves disposed upon said longitudinally disposed bracing members, and a plurality of collapsible bracing members disposed within said inflatable gas containing means.

19. The combination of an outer casing for an airship of the lighter than air type, a plurality of spaced-apart supporting members disposed within the casing, a plurality of longitudinally disposed bracing members disposed within the casing, inflatable gas containing means secured to certain of said spaced-apart supporting members, said inflatable gas containing means being provided 5 with a plurality of sleeves disposed upon said

longitudinally disposed bracing members, a plurality of collapsible bracing members disposed within said inflatable gas containing means, and means for placing and holding said collapsible bracing members under 15 bracing tension.

Signed at Chicago, in the county of Cook and State of Illinois, this 14th day of February, A. D. 1928.

OTTO GEISLER.
